UNITED STATES PATENT OFFICE.

CHARLES A. SWANSON, OF CHICAGO, ILLINOIS.

BUCKLE.

1,218,334.

Specification of Letters Patent.

Patented Mar. 6, 1917.

Application filed January 29, 1916. Serial No. 75,039.

To all whom it may concern:

Be it known that I, CHARLES A. SWANSON, a citizen of the United States, and a resident of the city of Chicago, county of Cook, 5 and State of Illinois, have invented certain new and useful Improvements in Buckles, of which the following is a specification.

My invention relates to improvements in strap buckles, and has for its object the production of a buckle which will be of durable 10 and economical construction, one which will be compact, and one which will be highly efficient in use.

Other objects will appear hereinafter.

The invention consists in the combinations 15 and arrangements of parts hereinafter described and claimed.

The invention will be best understood by reference to the accompanying drawing 20 forming a part of this specification, and in which,

Figure 1 is a top plan view of a buckle embodying the invention, showing the same connected with a strap,

Fig. 2 is a longitudinal section of Fig. 1, and

Fig. 3 is a side elevation of the construction, showing the buckle in operation.

The preferred form of construction, as 30 illustrated in the drawing, comprises a metallic frame consisting of front and rear parallel bars 1 and 2 and parallel side bars 3, the bars 3 being connected by a transversely extending stop bar 4 arranged at 35 the under side of the frame. The gripping member 5 of the buckle has a reduced rearward end 6 which loosely embraces the rear bar 2, the front end of said gripping member being serrated and so disposed as to be 40 adapted, when in operation, to coöperate with the front frame bar 1, as clearly shown in Fig. 3. The gripping member 5 is bent downwardly or depressed intermediate its ends so that when the gripping member is 45 in engagement with the stop bar 4, said depressed portion will be positioned directly behind the front frame bar 1.

Coöoperating with the buckle is a strap 7, one end of which is connected with the 50 buckle frame by means of an elongated metallic plate 8 substantially U-shaped in form, the bight portion of which loosely embraces the rear bar 2 of the buckle frame. The ends of member 8 embrace the corre-

sponding end of the strap, being secured 55 thereto by means of rivets 9. The bight portion of connecting member 8 is formed with a central slot 10 in order to accommodate the rearward reduced portion 6 of the gripping member 5, as clearly shown in 60 Fig. 1.

A keeper loop 11 is provided for coöperation with the end of the strap, as shown in Fig. 3. Said loop 11 is substantially rectangular in form, one of the longitudinal 65 sides thereof being arranged between the ends of connecting member 8 and interposed between the frame bar 2 and the adjacent end of the strap 7. With this arrangement, it will be seen that the loop 11 is loosely 70 mounted so as to permit of the same assuming a position in close proximity with or lying flat against the buckle or the connecting member 8, when not in use, as clearly shown in dotted lines in Fig. 2.

With a construction as set forth wherein the gripping member 5 and connecting member 8 both engage with the same bar of the buckle frame, an extremely simple and economical arrangement is provided, as well 80 as one possessing strength and firmness. The depression of stop bar 4 which allows the gripping member 5 to sink into the buckle frame, as seen in Fig. 2, results in an arrangement wherein the end of the strap 85 will lie close to the buckle and hence in an arrangement which is very compact when the strap is engaged with the buckle.

While I have illustrated and described the preferred form of construction for carrying my invention into effect, this is capable of variation and modification without departing from the spirit of the invention. I, therefore, do not wish to be limited to the precise details of construction set forth, but 95 desire to avail myself of such variations and modifications as come within the scope of the appended claim.

Having described my invention what I claim as new and desire to secure by Letters 100 Patent is:

A buckle comprising a frame having a rear bar; a gripping member pivotally connected with said rear bar; a strap for coöperation with said buckle; a connecting 105 member embracing said rear frame bar and having its ends bent back and fastened to one end of said strap for connecting said

parts; and a keeper loop for coöperation with said strap, said loop having one side arranged between said ends of said connecting member and interposed between said rear frame bar and the adjacent end of said strap, substantially as described.

In testimony whereof I have signed my

name to this specification in the presence of two subscribing witnesses.

CHARLES A. SWANSON.
